UNITED STATES PATENT OFFICE.

JOSEPH CHALLENDER, OF MANCHESTER, ENGLAND.

SILENT FLUSHING APPARATUS FOR WATER-CLOSETS OR URINALS.

SPECIFICATION forming part of Letters Patent No. 645,203, dated March 13, 1900.

Application filed October 1, 1898. Serial No. 692,449. (No model.)

To all whom it may concern:

Be it known that I, JOSEPH CHALLENDER, residing at 12 Moss Lane West, in the district of Moss Side, Manchester, in the county of Lancaster, England, have invented new and useful Improvements in Silent Flushing Apparatus for Water-Closets or Urinals, (for which I have made application for patent in Great Britain, No. 17,316, dated August 11, 1898,) of which the following is a specification.

My invention relates to improvements in flushing apparatus for water-closets and urinals, the object being to dispense with valves, siphons, or levers inside the cistern and the chain or pull, excepting from choice, thus rendering the closet silent up to delivery.

My improved system of flushing water-closets and the like consists of a float in the water-cistern which acts automatically in connection with a valve and catch inside a metal box containing said valve, which is placed in a convenient position between the water-cistern and the closet or urinal. The said valve can be opened and brought into use by a push or button, hereinafter described, or, if desired, by lowering or raising the closet-seat or by the opening or closing of a door or other mechanical contrivances. I attain these objects by the means illustrated in the accompanying drawings, in which—

Figure 1 is a longitudinal section of the water-supply cistern; Fig. 2, a vertical section, and Figs. 3 and 4 sectional plans, of the said valve-box, the latter at lines A A and B B of Fig. 1, respectively, the valve being shown removed in Fig. 3. Fig. 5 shows at a reduced scale a diagram of the whole flushing system.

Similar letters refer to similar parts throughout the several views.

In carrying out my invention and referring to Figs. 1, 2, 3, and 4, A is the box containing the said valve, which box may be constructed in any shape in one or more parts—say in two parts, as shown in Figs. 2, 3, and 4, an upper one a and a lower one a', which can be joined together by flanges or otherwise, and having an inlet b and outlet b' sufficiently large for the flushing-water to pass freely. The lower part a' contains an ordinary valve-seating c and a valve d, attached

to a bar or swivel e, which turns easily and is kept in position by lugs or stops f. The ends of the bar or swivel e are cranked upward or so made as to form projections e' e', adapted to be acted upon by the forked ends g g of a rod g', connected with the button or push g'', which rod is mounted in a stuffing-box h, formed on the valve-box A. This rod and button are not connected with but simply lift the valve d when pushed against the projections e' e' and when released are returned to their normal position by a spring i. In the upper part a, immediately over the valve d, but just under the inlet b, is fulcrumed to a spindle k a catch or lever l, one side of which is weighted and the other side opened out like a spreader or fan and slightly turned at its edge, which when at rest stands out horizontally under the inlet b of the valve-box A. (See full lines, Fig. 2.) In connection with this valve and catch a float m is employed in the water-cistern n, (see Fig. 1,) large enough to cover the orifice of the flush-pipe o, secured therein, which latter is formed with a seating o', while the said float carries an air-tube m', projecting on both sides and vertically guided by the bridge o''.

When the cistern n is charged with water, the float is buoyed over the flush-pipe o and kept in this position while the column of water in the pipe rests upon the valve d in the box.

Below the under side of the float m air-holes m' are formed in the air-tube m', which permit the air accumulated above the water in the flush-pipe o when nearly full and the float is on its seating to escape through the air-tube m', so as to prevent bubbling and noise.

The operation of the system is as follows: When it is desired to flush the water-closet p, the button g'', outside the valve-box A, is pressed in and immediately released, which action causes the valve d in the box A to be lifted into the position shown in dotted lines, Fig. 2. The column of water in the flush-pipe o being then allowed to descend presses the front or fan end of the catch-lever l down upon the end of the valve d and retains the same in its raised position until the closet is flushed. As the water descends in the cistern the float m descends also, and when the cistern is

nearly empty the float closes the orifice of the flush-pipe o , whereby the swirl and sucking noise usually created by the escape of water in ordinary cisterns is obviated. When the water has left the flush-pipe o , the weighted catch is freed from its pressure, and the weight of the catch then raises its fan end off the valve d and allows the same to fall and close. The water in the cistern n then flows slowly through the apertures q , formed in the upper end of the flush-pipe o , into the latter, and when charged the float rises off its seating o' again.

What I claim as my invention, and desire to secure by Letters Patent, is—

- 15 1. In apparatus for flushing water-closets, urinals and the like, in combination with a water-cistern n a float m having an air-escape tube m' formed with side holes m^2 , and a seating o' for the latter to operate upon, the said seating having lateral holes q which permit the water to run from the cistern n into the

flush-pipe o while the float m rests on the seating o' , all substantially as and for the purpose set forth.

25

2. The combination of the cistern n , the flush-pipe o , the valve-box A in the flush-pipe below the cistern, the valve d in the valve-box, the valve-operating push-rod g passing into the said valve-box, the valve-retaining catch l pivoted to the interior of the box above the valve d , all substantially as set forth.

3. In combination, the cistern n having a float m , the valve-box A containing a valve d , raised by a push-rod g, g' and retained by a weighted catch l subjected to the action of the column of water in the flush-pipe o , which valve-box is inserted into the latter, all substantially as and for the purpose set forth.
